UNITED STATES PATENT OFFICE.

AARON E. SMOLLEY, OF BROOKVILLE, INDIANA.

GAME APPARATUS.

SPECIFICATION forming part of Letters Patent No. 467,124, dated January 12, 1892.

Application filed January 19, 1891. Serial No. 378,228. (No model.)

To all whom it may concern:

Be it known that I, AARON E. SMOLLEY, a citizen of the United States, residing at Brookville, Indiana, have invented new and useful 5 Improvements in a Game Apparatus, of which the following is a specification.

My invention relates to game apparatus, its object being to provide a simple and inexpensive device designed, particularly, for the use 10 of the young of both sexes in a pastime combining instruction and amusement.

To this end the invention consists in a "game-board" in which is formed a central depression suitably marked into separate 15 spaces containing words, letters, or figures arranged either singly or in sentences or parts thereof and flanked by smaller depressions with suitable guideways leading therefrom to the larger central depression, whence 20 spherical balls may be projected into the larger depression and ultimately come to rest in some one of the spaces into which its flat area is divided, thus indicating the letter, figure, word, or sentence to be used in making 25 up a more or less intelligible result of a given number of plays for each player.

My invention is illustrated in the accompanying drawings, in which—

Figure 1 is a plan view of the apparatus 30 complete; Fig. 2, a corresponding cross-section of the same. Fig. 3 is a plan view of the apparatus, showing a polygonal form adapted to the use of a larger number of players.

Referring now more particularly to the 35 drawings, A designates a flat plate of any suitable material, (such as wood, metal, papier-maché, &c.,) having a central depression or "arena" a, preferably circular, flanked by small shallow depressions or "stations" B, 40 having one or more inclined guideways b leading thence to the arena a. The flat bottom of the arena is marked by concentric circles and radial cross-lines (or in any other manner) into separate spaces s, and in each 45 space is printed or stamped a letter of the alphabet, a figure or figures, a word, a sentence or part of a sentence, or a symbol of any kind. The selection between these will be governed by the main purpose to which the game is de- 50 voted, and will be better understood in connection with the following description of the mode of use in certain selected illustrations.

To select the simplest, suppose the spaces contain letters of the alphabet and two or more children are playing, each having a ball 55 or "marble" m and the apparatus is placed on a level table. The first player in order takes his ball from its station B and places it in any one of the inclined ways b leading from his station. The inclination of the guideway 60 causes the ball to roll out into the arena a, and it finally comes to rest, say, upon the space containing a letter "B." The second in order in like manner scores the letter "S," and the third and last scores "T." These letters 65 being written down, the ingenuity of the children is then taxed to guess words in which these letters can be employed—as, for example, "Boston," "best," "stub," "bistre," "tubs," &c., the child guessing the greatest number of 70 words being the winner of the game. It will be easily seen that this exercise not only stimulates the thinking faculties of the child, but increases his vocabulary, perfects his knowledge of correct spelling, and is otherwise improving and instructive, all being based upon 75 and growing out of a pleasant pastime, and, indeed, made part of it.

The analogous use of the apparatus with words to be framed into sentences or with 80 numbers to be added or otherwise dealt with arithmetically for older children will be obvious without further description. For youth or grown persons the selected words may have reference to peculiarities of disposition or appearance or relate to the possible destiny of 85 individuals or other accidents or incidents of social life, and the apparatus be thus adapted to use in the pastime of "fortune-telling." All these and other kindred constructions and 90 uses of the apparatus are within the purview of my invention.

As prepared for the market the apparatus is handsomely painted, varnished, or otherwise beautified and made attractive, and is 95 packed in a suitable containing-box, together with all adjuncts and printed instructions for use. I may also provide separate detachable cards, differing as above indicated, to form the bottom c of the arena, as indicated in Fig. 100 2, so that the scope and capacity of the device may be varied at will by the possessors.

I claim as my invention and desire to secure by Letters Patent of the United States—

1. A game apparatus of the character described, embodying a flat board or disk having a depressed central area continuously flat and divided into spaces with contained words, syllables, figures, or symbols by marks offering no impediment to the free rolling of a ball, combined with one or more ball-stations adjacent to said depressed area and connected therewith by inclined ways, substantially as set forth.
2. A game apparatus consisting of a flat board or plate having a depressed central

area flanked by ball-stations, in combination with removable bottom boards or cards for the central depressed area, divided into spaces containing letters, figures, words, or symbols, substantially as and for the purpose set forth, 15

In testimony whereof I have hereunto set my hand in the presence of two subscribing witnesses.

AARON E. SMOLLEY.
